UNITED STATES PATENT OFFICE.

CHRISTIAN A. LAUSEN, OF COUNCIL BLUFFS, IOWA.

FURNACE.

Application filed June 17, 1924. Serial No. 720,606.

To all whom it may concern:

Be it known that CHRISTIAN A. LAUSEN, a citizen of the United States, residing at Council Bluffs, in the county of Pottawat-

5 tamie and State of Iowa, has invented cer-
tain new and useful Improvements in Fur-
naces, of which the following is a specifi-
cation, reference being had therein to the
accompanying drawings.

10 The invention relates to furnaces of the
circulating air type, and has for its object
to provide a device of this character where-
by an efficient circulation of heated air will
be maintained and wherein a maximum
15 number of heat units will be conserved with-
in the fire box while combustion is taking
place therein. Also to provide a furnace
wherein the minimum amount of heat units
will be lost through the chimney, and the
20 maximum heating of the recirculating air
obtained.

A further object is to provide a furnace
with water jackets, positioned whereby they
will absorb and convey heat units in to the
25 volume of water contained therein for gen-
erating aqueous vapor or steam, which in
turn is conveyed to the fire box and there
decomposed into their elements for recom-
bustion to augment the heating efficiency of
30 the furnace.

A further object is to dispose the water
jackets on opposite sides of the furnace
casing, and to provide pipes connected to
35 their upper sides, which pipes extend down-
wardly and inwardly towards each other
beneath the furnace grate and terminate in
a perforated member through which the
vapors pass to the fuel on the grate thereby
40 rendering the same more volatile.

45 A further object is to provide a pipe con-
necting one of the water jackets to the
hood of the furnace and forming means
whereby aqueous vapor or steam may be
discharged into the air after it is heated, and
50 before it passes through the pipe leading to
the registers of a building, thereby mois-
tening the air.

With the above and other objects in view
the invention resides in the combination and
55 arrangement of parts as hereinafter set
forth, shown in the drawings, described and
claimed, it being understood that changes
in the precise embodiment of the invention
may be made within the scope of what is
55 claimed without departing from the spirit
of the invention.

In the drawings:—

Figure 1 is a perspective view of the fur-
nace, parts being broken away to better
show the structure. 60

Figure 2 is a vertical transverse sectional
view through the furnace.

Figure 3 is a detail sectional view through
a portion of the front wall of the furnace
casing, and the hood. 65

Figure 4 is a vertical longitudinal sec-
tional view through the furnace.

Referring to the drawing, the numeral 1
designates the main casing of the furnace
which is preferably rectangular, and ex-
tending through the front wall 2, and the
rear wall 3 are upwardly and forwardly
inclined pipes or flues 4, through which air
passes from the supply pipe 5, which con-
ducts air to the chamber 6 of the hood 7. 70
The air in passing through the flues 4 is
heated by fire upon the grate 8 disposed
below the flues and rises into the forward
hood 9, from which forward hood the heated
air passes through the pipe 10 to the various
rooms of a building. The products of com-
bustion pass around the flues 4 heating the
air therein, and discharge through the pipe
11 which leads to a chimney in the usual
manner. It has been found that a large
percentage of the heat units in a furnace
pass out the chimney incident to improper
75 combustion or construction. It has also
been found that by supplying steam or
aqueous vapors to the fuel, during the com-
bustion, the maximum heat units are ob-
tained and conserved for heating purposes,
80 and to accomplish this result the opposite
sides of the casing 1 adjacent the sides of
the fire box above the grate 8 are provided
with water jackets 12, in which water is
placed. Connected at 13 to the upper sides
85 of the water jackets are pipes 14, which pipes
extend downwardly and inwardly to posi-
tions below the grate 8, and are connected
to a perforated chambered member 15
through the perforations 16 of which the
90 aqueous vapors or steam is discharged into
the fuel on the grate 8, thereby through the
recomposition of hydrogen and oxygen gases,
95 previous decomposed through the energy of
heat units increasing the combustion and
insuring the maximum amount of heat units
obtained from the fuel. The water in the
water jackets 12 is maintained heated by
100 heat radiated through the side walls 1^a of
the casing 1, therefore it will be seen that

95

100

105

110

the heat radiated from the casing is utilized for heating the water and is not entirely lost.

One of the water jackets 12 has connected thereto, above the water level therein, a pipe 17, which pipe is connected to the lower end of the forward hood 9 at 18, and forms means for conducting aqueous vapors and steam to the hood 7 where it will mingle with the heated air passing from the flues 4 to the pipe 10; consequently said heated air will be partially moistened when it reaches a room, whereby the oxygen is replenished to a certain extent.

From the above it will be seen that a furnace is provided wherein aqueous vapors or steam are conveyed to the fire box of the furnace thereby insuring a maximum efficiency of combustion and consequently the utilization of the maximum heat units obtainable from the fuel. It will also be seen that aqueous vapors are conveyed to the heated air after the passage from the flues and consequently the air will be moistened when it enters the room of a building.

The invention having been set forth what is claimed as new and useful is:—

1. The combination with a hot air furnace, said furnace comprising a casing, a fire box having a grate therein, and flues above said fire box, of means for supplying aqueous vapors and steam to the fire box, said means comprising water jackets carried by the casing and heated by the fire box and means for conveying the aqueous vapors and steam from the water jackets and discharging the same beneath the grate.

2. The combination with a hot air furnace, said furnace comprising a casing, a fire box having a grate therein, and flues above said fire box and through which air

passes, of means for generating and supplying aqueous vapors and steam to the fire box, said means comprising water jackets carried by the casing in registration with the fire box and outside the casing, pipes connected to said water jackets adjacent their upper sides, said pipes extending downwardly and inwardly to positions below the grate and a perforated member carried by said pipes and positioned to discharge aqueous vapors and steam through the grate into the fire box.

3. The combination with a hot air furnace, said furnace comprising a casing, a fire box having a grate therein, and flues above said fire box, and a hood having a heat collecting chamber into which the air from the flues is discharged, of means for supplying aqueous vapors and steam to the fire box upwardly through the grate, said vapors and steam being generated by heat radiated from the fire box and means for discharging a portion of said vapors and steam into the heat collecting chamber of the hood.

4. The combination with a furnace comprising a casing, a fire box, and flues, and a heat collecting hood into which the flues discharge, of means for supplying aqueous vapors and steam to said fire box and heat collecting hood, said means comprising water jackets carried by the opposite sides of the casing and heated by heat radiated from the fire box, pipes carried by said water jackets adjacent their upper sides and discharging into the fire box, and a pipe carried by one of the water jackets and discharging into the heat collecting hood.

In testimony whereof I hereunto affix my signature.

CHRISTIAN A. LAUSEN.
